No. 37,480.

Patented July 11, 1905.

UNITED STATES PATENT OFFICE.

RICHARD F. OUTCAULT, OF FLUSHING, NEW YORK, ASSIGNOR TO THEODORE METZELER AND FREDERIC L. DENIVELLE, OF NEW YORK, N. Y.

DESIGN FOR A STATUETTE.

SPECIFICATION forming part of Design No. 37,480, dated July 11, 1905.

Application filed April 20, 1905. Serial No. 256,690. Term of patent 7 years.

To all whom it may concern:

Be it known that I, RICHARD F. OUTCAULT, a citizen of the United States, residing at 54 North Parsons avenue, Flushing, county of Queens, State of New York, have invented a new, original, and ornamental Design for a Statuette, of which the following is a full and exact specification.

Reference is to be had to the drawing accompanying this specification, which is a front elevation of the statuette, showing my design.

I claim—

The ornamental design for a statuette, as shown.

RICHARD F. OUTCAULT.

Witnesses:

MARY J. OUTCAULT,
ETHEL STURGIS.
